CLAIM

The ornamental design for a infant play mat, as shown and described.

DESCRIPTION

FIG. 1 is a front perspective view of the infant play mat, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, bottom, rear plan view of the infant play mat, in an alternate configuration.

The broken lines shown along the perimeter and within the rectangles of the infant play mat in FIGS. 1, 2, 3, 6, 7, and 8 illustrates seaming in the fabric. The remaining broken lines in the drawings illustrate portions of the infant play mat, which form no part of the claimed design.
